CLAIM

The ornamental design for an ambidextrous survival self-defense tool, as shown and described.

DESCRIPTION

FIG. 1 shows a perspective view of an ambidextrous survival self-defense tool.

FIG. 2 shows a left side view of the ambidextrous survival self-defense tool.

FIG. 3 shows a right side view of the ambidextrous survival self-defense tool.

FIG. 4 shows a top plan view of the ambidextrous survival self-defense tool.

FIG. 5 shows a bottom plan view of the ambidextrous survival self-defense tool.

FIG. 6 shows a front view of the ambidextrous survival self-defense tool; and,

FIG. 7 shows a rear view of the ambidextrous survival self-defense tool.

The shade lines in the Figures show contour and not surface ornamentation.
